UNITED STATES PATENT OFFICE.

JOHN RICE, OF BURLINGTON, NEW JERSEY.

DEVICE FOR CASTING INDICIA ON PIPES.

Application filed October 23, 1923. Serial No. 670,331.

To all whom it may concern:

Be it known that I, JOHN RICE, a citizen of the United States, residing at Burlington, in the county of Burlington and State 5 of New Jersey, have invented certain new and useful Improvements in a Device for Casting Indicia on Pipes, of which the following is a specification.

The present invention relates to casting 10 apparatus particularly for use in machines of the centrifugal type used for making cast iron pipe.

An object of the invention is to provide 15 a means for casting in the pipe the name, trade mark, or other lettering or configurations which are to be made as an integral part of the cast iron pipe, and which may be formed in the pipe during the centrifugal casting operation.

20 There are various machines for casting pipe by centrifugal action and a prominent type of machine is that disclosed in the United States Letters Patent Number 1,347,582 granted July 27, 1920 to J. B. 25 Ladd. It is the purpose of this invention to provide a device which may be used with all rotary machines for casting the characters in the exterior body wall of the cast iron pipe.

30 A further object of the invention is to provide a character casting device which may be applied to the rotary mould body for producing outstanding characters or symbols upon the exterior of the cast article and which are so formed that they will not interfere with the withdrawal of the finished product after the casting operation.

A still further object of the invention is 40 to provide a moulding device for detachable mounting in the rotary mould body and which may have characters or symbols thereon which are individual to the person or company manufacturing the pipe and which admit of the ready interchanging of 45 the moulding devices so as to meet conditions of use in marking different grades of pipes or pipes for different manufacturers.

The above and various other objects and 50 advantages of this invention will in part be described in and in part understood from the following detailed description of the present preferred embodiment, the same being illustrated in the accompanying drawings, wherein:

Fig. 1 is a fragmentary sectional view taken longitudinally and vertically through 65 a centrifugal pipe moulding machine having the character moulding device of this invention applied thereto.

Fig. 2 is an enlarged fragmentary view showing in section the bell end of the mould 60 body of the machine with the moulding device applied thereto.

Fig. 3 is an outer end view of the same.

Fig. 4 is a fragmentary side elevation of 65 the bell end of a pipe moulded with the characters thereon in accordance with this invention.

Fig. 5 is a transverse section through the same taken on the line 5—5 of Fig. 4.

Fig. 6 is a fragmentary enlarged view of 70 a portion of the moulding device, showing a plan view thereof with a character formed therein according to the present invention.

Fig. 7 is a fragmentary enlarged section 75 taken longitudinally through the moulding device mounted in the mould body, showing the clearance angles of the bottoms of the character grooves.

Fig. 8 is a view similar to Fig. 6 but showing a different character in the moulding 80 device, and

Fig. 9 is a view similar to Fig. 7 but showing the character of Fig. 8.

Referring to the drawings, and first to Fig. 1 there is shown a portion of the machine which is disclosed in the patent to Ladd Number 1,347,582, above referred to. The present Figure 1 shows a pedestal 15 in which is mounted on bearings 16 the head 17 of a mould housing 18. The mould housing 90 is surrounded by a stationary shell 19 and the housing carries therein a mould body 20 shaped to the desired size and configuration of the cast product. The mould body 20 has a bell end 21 into which is removably fitted 95 the moulding device of this invention.

The moulding device comprises an annular body or liner 22 which is exteriorly threaded for detachable engagement with internal threads 23 within the bell end, the bell end 21 being counterbored and tapped 10 to receive the liner or moulding device 22 and the latter being given a thickness corresponding to that of the material removed from the inner wall of the bell end 21. The liner 22 is threaded into the bell end 21 in 10 a direction counter to that in which the

mould body 20 turns so that there will be no likelihood of the liner 21 becoming loose or disengaged from the bell end.

The inner wall of the liner 22 is bored 5 out to the conventional size and shape of the hub and spigot pipe, and the characters, which may be letters, symbols or a combination of the two, are sunk in the inner wall of the liner 22 as shown at 24 in Fig. 1, and 10 are located at the inner end of the liner at that portion where the bell end merges or converges into the body of the pipe.

Advantage is taken of this inclined or converging wall of the bell end of the mould 15 body to provide the characters in outstanding relation or relief on the exterior surface of the pipe so that the pipe may be easily removed from the mould body by withdrawing the pipe through the bell end 21 without 20 injury to the mould body or to the cast pipe. As shown in Figs. 7 and 9 the transverse grooves or depressions in the inner wall of the liner 22 are flared outwardly at their bottom walls at an angle of substantially 25 three degrees to a line parallel with the axis of the liner so that the raised ribs or characters on the exterior surface of the moulded article may recede from said bottom walls without frictional contact with 30 the faces and thus without injury to either the article or the mould.

In use, the liner or moulding device 22 with its characters 24 is threaded into the bell end 21 of the mould body and the 35 moulten metal is placed in the mould body in the usual manner, and the mould housing with the mould body rotated at the desired high rate of speed. The centrifugal force causes the moulten material to enter the cavities of the characters 24 and to also seek a certain surface level as compared with the length of the mould body and thus form a pipe 25 of uniform thickness. The metal which flows into the cavities of the characters 40 45 becomes set and when the pipe 25 with its bell end is withdrawn through the bell end 21 of the mould body, the formed characters 26 on the exterior surface of the pipe 25 are free to move directly away from the surfaces of the cavities of the characters 24 by virtue of the outward flaring of the bottoms of the cavities. It will be also observed from Figs. 7 and 9 that the outer 50 55 walls of the cavities merge into the inclined wall of the liner 22 so that no shoulders or ribs interfere in any way with the direct removal of the pipe and its formed characters 26.

It is of course understood that various 60 changes in the construction and shape of the liner or moulding device 22 may be made, and also that the cavities 24 in the inner wall of the liner may be given various configurations and sizes to cast the names of manufacturers of the cast article and the trade 65

mark or symbol by which the goods may be later identified, without departing from the spirit of the invention, all of these various changes being restricted only by the scope of the following claims.

70

What is claimed is:

1. The combination with a centrifugal casting machine having a tubular mould body with a bell end, a liner detachably fitted in said bell end and having an inner wall conforming to the contour of the removed inner wall of the bell end, said liner having character grooves formed in its inner wall at its contracting inner end, said grooves having their inner walls flaring outwardly at an angle sufficient to liberate characters formed on the cast article as the latter is withdrawn through said bell end. 75

2. The combination with a centrifugal casting machine having a rotary tubular mould with a bell end, a liner detachably threaded in said bell end and having its inner wall conforming to the configuration of the bell end, said liner having in its inner wall depressions forming matrices of characters in the inner wall of the liner and at the converging inner end thereof, said depressions facing angularly outward through the bell end and having their inner walls flaring outwardly from the axis of the liner for liberating characters cast integral upon the exterior surface of the article moulded. 90

3. The combination with a centrifugal pipe casting machine having a tubular rotary mould with a bell end, a ring shaped moulding device externally threaded for detachable engagement in said bell end of the mould body, said moulding device having an inner wall converging at the inner end of the device to form an inclined wall and having in said inclined wall character grooves into which the metal treated is adapted to be cast to form characters upon the exterior surface of a pipe, said character grooves having their outer sides merging into the inclined wall of the moulding device and having their bottoms flaring outwardly toward the end of the mould body for liberating the characters cast upon the outer face of the pipe. 100 105 110

4. In a rotary casting machine a centrifugal mould providing a passageway therethrough having a moulding surface sloping with respect to the axis of the mould, said sloping surface having character forming depressions therein so constructed that an article moulded may be withdrawn from an end of the mould passageway. 120

5. In combination with a rotary casting machine including a mould body rotatably supported therein, a removable liner fitted in the mould body by screw threading therein in a direction counter to the normal direction of travel of said mould body, said liner 125 130

having character forming depressions therein into which the moulded material is adapted to be formed by centrifugal pressure.

6. In a rotary casting machine a mould providing a passageway therein into which the moulten material is to be received, said mould passageway including an inclined surface over which the moulten metal will flow, said inclined surface being provided 10 with character forming depressions therein the outermost edges of which character forming depressions merge into the sloping surface of the mould and the innermost edges of which characters provide shoulders 15 arranged obliquely to the sloping moulding surface of said mould.

7. In combination with a rotary casting machine, a mould therefor providing a passageway therethrough adapted to receive 20 the moulten metal, said passageway including a portion of its surface therein inclined with respect to the axis of said passageway, said inclined surface having character forming depressions therein the bottom surfaces 25 of which slope in diverging acute angular relation with respect to the axis of the mould passageway toward one end of said passageway.

8. In a centrifugal casting machine a rotary mould providing a passageway therein, 30 said casting passageway at an end thereof being provided with a bell shaped cavity providing sloping surfaces inclined with respect to the axis of the passageway, said sloping surfaces having character forming 35 depressions therein the outermost edges of which merge into the sloping surface of the mould passageway and the innermost edge portions of which depressions provide shoulders arranged obliquely to the sloping 40 surface of said mould passageway, the bottom surfaces of said depressions being arranged in diverging acute angular relation to the axis of the mould toward the larger 45 end of said passageway.

9. In a rotary casting machine a centrifugal mould providing a passageway therethrough having a moulding surface sloping with respect to the axis of the mould and towards an open end of said mould, said 50 sloping surface having character forming depressions therein facing said open end of the mould whereby an article moulded may be easily withdrawn from said open end of the mould.

JOHN RICE.
